United States Patent Office.

JORDAN L. MOTT, OF MOTT HAVEN, NEW YORK.

Design No. 3,721, dated October 19, 1869.

DESIGN FOR AN IRON WASH-STAND SLAB.

The Schedule referred to in these Letters Patent and making part of the same.

To all whom it may concern:

Be it known that I, JORDAN L. MOTT, of Mott Haven, in the county of Westchester, and State of New York, have originated a new Design for an Iron Wash-Stand Slab, of which the following is a full, clear, and exact description, reference being had to the accompanying drawing, forming part of this specification, and in which—

Figure 1 represents a plan of a wash-stand slab, made according to my new design, and

Figure 2, a section of the same, taken as indicated by the line x x in fig. 1.

Figure 3 is a sectional view, on an enlarged scale, of one of the sides, border, and portion of the base-plate of the slab.

Similar letters of reference indicate corresponding parts.

My new design for iron wash-stand slabs, as depicted in the accompanying drawing, embraces a flat overlapping border, of straight configuration at its back a , and straight, in right-angled directions to said back portion, at its sides b b , for a portion of their length, excepting at their inner union with such back portion, where they have a concave configuration, as at c c , and said sides b b of such flat border being curved, as at d d , in front, to join the front portion e of said border, which front portion lies parallel with the back portion a .

The sides f f of the stand, all around it, which unite the base-plate g with the flat overlapping border hereinbefore referred to, dip downward, for the most part, in straight lines, inclining inwardly in a downward direction, but forming their junction with the base-plate by rounded or hollow angles h h , and their junction with the flat border by angles or bends i i , which are curved where they join the sides f f , but straight or flat, or nearly so, where they meet the flat border, so as to present a sharp inner edge, k k , all around said border.

The base-plate g has its circular basin-aperture, or opening m through it bordered or bound by a flange, n , which is rounded on its upper edge, and shelved or rounded off below, on its inside, and is made to dip below the under surface of the plate g , to which, at its back or outer surface, it forms a straight junction, at right angles or thereabout with the under surface of said plate.

What I claim as my invention, and desire to secure by Letters Patent, is—

The design for iron wash-stand slabs, as herein described, and represented in the accompanying drawing.

JORDAN L. MOTT.
